UNITED STATES PATENT OFFICE.

WILLIAM M. BELLVILLE, OF CANNELTON, INDIANA.

ROTARY DISPLAY-TABLE FOR STORE-WINDOWS.

1,208,457.

Specification of Letters Patent. Patented Dec. 12, 1916.

Application filed December 14, 1915. Serial No. 66,835.

To all whom it may concern:

Be it known that I, WILLIAM M. BELLVILLE, a citizen of the United States, residing at Cannelton, in the county of Perry and State of Indiana, have invented certain new and useful Improvements in Rotary Display-Tables for Store-Windows; and I do hereby declare the following to be a full, clear, and exact description of the invention, 5 such as will enable others skilled in the art to which it appertains to make and use the same, reference being had to the accompanying drawings, and to the letters and figures of reference marked thereon, which form a 10 part of this specification.

This invention relates to new and useful improvements in rotary tables for show window purposes in stores, etc., and consists in the provision of a simple and efficient 20 device of this nature having various details of construction, combinations and arrangements of parts which will be hereinafter fully described, shown in the accompanying drawings and then specifically defined in the 25 appended claim.

My invention is illustrated in the accompanying drawings, in which:

Figure 1 is a top plan view. Fig. 2 is a sectional view vertically through the table. 30 Fig. 3 is a transverse sectional view. Fig. 4 is a bottom view of one of the tables.

Reference now being had to the details of the drawings by letter, A designates the base of the table having a circumferential flange B, and C designates a circular series 35 of teeth or pins which project horizontally from the inner surface of the flange at any suitable location. Rising from said base is a projection D having a ball bearing D' 40 therein upon which the pintle E rests and which projects from the lower surface of the rotatable table F. Said table is mounted upon rollers H which travel upon the upper edge of the flange B and has a downwardly 45 extending flange I adjacent to its periphery

and which fits over the flange B. Mounted upon the table E are the smaller rotatable tables K, each of which has roller bearings L underneath the same and which rest upon the table F, and the pintle N of each table 50 K is connected with a gear wheel R having teeth S thereon which are adapted to engage with the teeth C.

The operation of the rotary table will be readily understood and is as follows:—The 55 table F may be given a rotary movement in any suitable way, either by power or by hand and, as it rotates, the intermeshing teeth C and S will cause the rings R to rotate and also the small tables K. 60

By the provision of a rotary table made in accordance with my invention, it will be noted that a simple and efficient apparatus is afforded whereby a large surface may be employed for displaying articles of various 65 kinds and, by the rotary movements of the parts, will bring the articles successively to the front where they may be visible.

What I claim to be new is:—

A display table for store windows, etc., 70 comprising a circular base with a circumferential flange having a series of annular teeth projecting from its inner face, a rotatable table having a downwardly extending flange telescoping over the flange of the 75 base, spaced apart therefrom, a post having a bearing centrally in the base and fixed to said table, pintles mounted upon said table, tables upon said pintles, roller bearings upon the tables which are mounted upon 80 said pintles, and gear wheels fixed to the pintles and meshing with the gear teeth upon the flange of the base.

In testimony whereof I hereunto affix my signature in presence of two witnesses.

WILLIAM M. BELLVILLE.

Witnesses:

JOHN W. HANBLETON,
JOSEPH M. HIRSCH.
